Primary Examiner — Marianne Pandozzi(74) *Attorney, Agent, or Firm* — Davis Wright Tremaine LLP; George C. Rondeau, Jr.(57) **CLAIM**

The ornamental design for a beverage container, as shown and described.

DESCRIPTION

FIG. 1 is a top front perspective view of a beverage container showing my new design.

FIG. 2 is a front elevational view thereof, the rear, left side and right side elevational views being identical.

FIG. 3 is a top plan view thereof; and,

FIG. 4 is a bottom plan view thereof.

The broken lines represent portions of the beverage container that form no part of the claim.
